His Attorney.

UNITED STATES PATENT OFFICE.

IVANHOE H. SCLATER, OF PITTSFIELD, MASSACHUSETTS, ASSIGNOR TO GENERAL ELECTRIC COMPANY, A CORPORATION OF NEW YORK.

ELECTRICAL APPARATUS.

1,315,867.

Specification of Letters Patent. Patented Sept. 9, 1919.

Application filed December 24, 1917. Serial No. 208,575.

To all whom it may concern:

Be it known that I, IVANHOE H. SCLATER, a citizen of the United States, residing at Pittsfield, in the county of Berkshire, State 5 of Massachusetts, have invented certain new and useful Improvements in Electrical Apparatus, of which the following is a specification.

My invention relates to electrical induction apparatus, such for example as transformers, auto-transformers, some reactances, etc.; my invention relates particularly, however, to reactances provided with cores of magnetic material. One object of my invention 10 is to improve the construction and operating characteristics of those devices of the class indicated, the cores of which have "air gaps" or interruptions in the magnetic circuit; another object is to provide such devices with more suitable gaps or interruptions in the magnetic circuit thereof. Other objects will appear from the matter herein-after. For simplicity and because my invention relates particularly to such devices, 15 I shall hereafter mostly describe my invention with reference to reactances; its application to other induction apparatus will be understood therefrom.

It is desirable to provide the cores of magnetic material of some reactances with "air gaps", or interruptions in the magnetic circuit transverse to the lines of magnetic flux, in order to prevent or limit the magnetic saturation of the cores and in that way allow 20 the use of smaller cores. Generally these gaps are preferably located in the parts of the cores inclosed by the windings. When considerable interruption of the magnetic circuit is necessary, a plurality of small gaps 25 are preferable to a single large gap, for a large gap causes undue "fringing" of magnetic flux about the gap and undue leakage of the flux. In "fringing", a part of the flux crosses the gap curves outwardly from 30 the core into the space for the windings, thereby increasing the eddy currents and heating; by leakage is meant that part of the flux completes its path outside the path through the core and therefore without inductively affecting the whole of the winding as it is desired the flux should do. Heretofore it has been customary to use both 35 complete gaps, or gaps extending completely across the magnetic circuit, and "bridged gaps" which extend only partly across the

magnetic circuit,—but not both types in the same core. Where one small gap in each leg of the core is sufficient, as in small reactances for example, it has been customary to use complete gaps. Complete gaps are 60 unsatisfactory, however, for reactances where a number of gaps are required in each core leg, for a number of complete gaps in any one core leg results in detaching one or more parts of the core from the remainder and there is no satisfactory simple way known for holding such detached parts in place when the core gaps are within the windings. Consequently "bridged gaps", 65 extending only partly across the core, have been used wherever a number of gaps per core leg are required within the winding, for such gaps eliminate the devices for holding the (otherwise) detached core parts in place. While bridged gaps are thus satisfactory from a mechanical point of view, such bridged gaps have been found to introduce higher harmonics into the electric circuits and higher harmonics are undesirable in electric circuits, as is well understood, on account of the increased operating losses and for other reasons. 70

Now I have found that it is possible by combining complete gaps and bridged gaps to materially avoid the undesirable features of each type of gap, and that a combination of the two types of gaps greatly improves the device and the operating characteristics thereof. Accordingly my invention consists, 75 briefly, in providing each core leg with a single complete gap and in addition as many more bridged gaps as may be necessary to secure the desired interruption of the magnetic circuit. In such a reactance there are 80 no detached core parts, and hence no devices particularly for supporting such detached parts, and the harmonics introduced into the electric circuits may be reduced to a low value without introducing prohibitive 85 fringing of the flux at the complete gaps. 90

In the accompanying drawing and the following description I have illustrated and described in some detail the best embodiment of my invention of which I am now aware. Figure 1 diagrammatically represents in elevation a reactance embodying my invention, the windings being broken away in part to show the core legs. Fig. 2 is a sectional view of one of the core legs looking in the direction of the arrows 2—2 105 110

of Fig. 1. Figs. 3 and 4 show parts of the narrow and the wide laminations of the core at both sides of the complete gaps.

The reactance of Fig. 1 in general is very similar to those heretofore known. It consists essentially of a core 10, generally rectangular in outline, and providing the winding legs 11 and 12. The core is laminated in the well-known manner and each winding leg is cruciform in cross-section. Combined core clamps and coil supports 15, each comprising in general an L-shaped member, are disposed as usual at the sides of each yoke of the core and are tightly clamped to the yokes by the bolts 16. A bolt 17 at each side of the reactance extends substantially parallel to the winding legs and passes through the flanges of the clamping members 15 at the same side of the core. These bolts 17 clamp the top of the reactance to the bottom and render the whole device a strong unitary structure in spite of the gaps extending completely across the magnetic circuit as hereinafter described in detail.

The windings 18 and 19 surround the winding legs 11 and 12 respectively and are supported by and between the flanges of the clamps 15 as illustrated.

Each winding leg is provided with one complete gap 22, extending completely across and completely interrupting the same, and with a plurality of "bridged" gaps 23 extending only partly across each lamination. Figs. 3 and 4 perhaps better illustrate the gaps. Fig. 3 illustrates one of the narrow layers or laminations of one of the winding legs, that is, one of the laminations occupying one of the parts 25 of the core leg (see Fig. 2). Fig. 4 shows one of the wide laminations or one of the laminations occupying the part 26 of the core leg. As will be seen from Figs. 3 and 4, each lamination of magnetic material is provided with a gap 22 extending completely across it; the path of the flux through this lamination is completely interrupted at 22. Each lamination is likewise provided with "bridged" gaps 23, a small width of the magnetic material being left opposite each of the gaps 23 at the extreme edges of the laminations. The gaps in the different laminations are so disposed that all the gaps 22 of all the laminations in any one core leg are arranged opposite each other; and likewise each gap 23 in any one lamination is arranged opposite a similar gap in the laminations adjacent it. Thus

the core legs, as well as each lamination thereof, is completely interrupted at 22, and the bridged gaps 23 in the different laminations result in holes completely through the core leg. This arrangement of the gaps is illustrated in Fig. 1. The complete gap 22 in each core leg is filled with some strong non-magnetic material; then as the nuts at the ends of the bolts 17 are screwed down, the ends of the lamination at the gaps 22 tightly compress the filling material and the whole reactance has great mechanical strength. The gaps 23 may also be filled with non-magnetic material if desired. For mechanical strength the non-magnetic filling material of each of the gaps 22 and 23 is preferably applied as a single block or in the form of a number of layers extending transversely to the axis of the winding leg.

While I have described the principle of my invention and the best mode I have contemplated for applying this principle, other modifications will occur to those skilled in this art and I aim in the appended claims to cover all modifications which do not involve a departure from the spirit and scope of my invention.

What I claim as new and desire to secure by Letters Patent of the United States, is:—

1. Electrical apparatus comprising a core of magnetic material provided with gaps, and windings surrounding said core, said gaps including a gap extending completely across the magnetic circuit and a bridged gap extending partially across the magnetic circuit.

2. Electrical induction apparatus comprising a core of magnetic material provided with gaps to prevent the saturation thereof, and windings on said core, said gaps being located in a portion of the core surrounded by said windings and including a gap extending completely across the magnetic circuit and a bridged gap extending partially across said magnetic circuit.

3. A core of magnetic material and windings thereon forming a reactance, said core being provided with gaps within said windings, said gaps including a gap extending completely across the magnetic circuit and a plurality of bridged gaps each extending partially across the magnetic circuit.

In witness whereof, I have hereunto set my hand this 21st day of December 1917.

IVANHOE H. SCLATER.
